ATTORNEY

UNITED STATES PATENT OFFICE.

CHARLES WHITTINGHAM, OF CLEVELAND, OHIO, ASSIGNOR TO THE CLEVELAND FOUNDRY COMPANY, OF SAME PLACE.

DESIGN FOR A GRATE FOR OIL-STOVES.

SPECIFICATION forming part of Design No. 24,394, dated June 11, 1895.

Application filed May 13, 1895. Serial No. 549,204. Term of patent 7 years.

To all whom it may concern:

Be it known that I, CHARLES WHITTINGHAM, a citizen of the United States, residing at Cleveland, in the county of Cuyahoga and State of Ohio, have invented and produced a new and original Design for Grates for Oil and Vapor Stoves, of which the following is a specification, reference being made to the accompanying drawing, showing the parts thereof.

My invention relates to a new and original design for grates for oil and vapor stoves, and the leading and characteristic feature of the design is the shape and configuration thereof. Thus, in the accompanying drawing, we have a rectangular figure ornamented with a border having two plain surfaces, —2—

and —3— substantially at right angles to each other; a flat ring —4— lying inside this border in the same plane therewith and alternately long and short flat bars —5—, which have scallops —6— in their top edges and scallops —8— and —9— in their lower edges, at either side of said ring. These bars —5— rise to a common plane above the frame and have the appearance of standing edgewise alone on the said border and ring.

What I claim is—

The design for a grate for oil or vapor stoves, substantially as shown and described.

CHARLES WHITTINGHAM.
